COMBINATION BILL AND MONEY FILE

Walter Kowalczyk, 3396 12th St., Wyandotte, Mich.

Filed Mar. 4, 1960, Ser. No. 59,612

Term of patent 14 years

(Cl. D29—23)

FIG. 1

FIG. 2

FIG. 4

FIG. 5

FIG. 3

FIG. 6

FIG. 7

FIG. 8

FIG. 1 is a reduced-scale perspective view of a combination bill and money file, showing my new design;

FIG. 2 is a reduced-scale perspective view of the device showing the adhesive mounting panel;

FIG. 3 is a larger-scale front elevational view with the door in open position;

FIG. 4 is a top plan view of the device;

FIG. 5 is a left side elevational view of the device;

FIG. 6 is a right side elevational view of the device;

FIG. 7 is a bottom plan view of the device; and

FIG. 8 is an enlarged front perspective view with the door in partially open position.

The dominant features of my design are shown in full

lines, and the broken line showing of a pencil and note pad is for illustrative purposes only.

I claim:

The ornamental design for a combination bill and money file, substantially as shown and described.
